UNITED STATES PATENT OFFICE.

EMMET P. GRAY, OF DETROIT, MICHIGAN, ASSIGNOR TO GRAY MANUFACTURING COMPANY OF DETROIT, OF DETROIT, MICHIGAN, A CORPORATION OF MICHIGAN.

WHISTLE.

No. 821,358.

Specification of Letters Patent.

Patented May 22, 1906.

Application filed April 17, 1905. Serial No. 256,129.

To all whom it may concern:

Be it known that I, EMMET P. GRAY, a citizen of the United States, and a resident of Detroit, in the county of Wayne and State of Michigan, have invented a new and useful 5 Whistle, of which the following is a specification.

My invention relates to that class of whistles in which the sound is produced by the 10 passage of steam, air, or gas through the same when said fluids are under pressure, and the particular type of whistle to which my improvements are adapted is that in which the chamber within the bell is divided into a plurality of sound-spaces by means of partitions, the length of the sound-spaces being varied 15 so that the single whistle produces a sound similar to that created by a chime of whistles.

20 The objects of my improvements are to provide a whistle of this kind with an auxiliary bell on the outside of the lower end of the whistle-bell for the purpose of lowering the musical note of the whistle, to provide a 25 whistle with a bell-shaped guard that shall prevent dirt and mud from flying up and stopping the operation of the whistle when used on the muffler of automobiles, and to provide a whistle of this type that shall be 30 strong and simple and may be constructed at a minimum cost. I attain these objects by the construction illustrated in the accompanying drawings, in which—

Figure 1 is a central longitudinal cross-section of my preferred form of whistle. Fig. 2 35 is a general view of the same. Fig. 3 is a view of the bell. Fig. 4 is a cross-section on the line 4-4 of Fig. 1. Fig. 5 is a view of the lower end of the whistle shown in Fig. 2.

40 Fig. 6 is a cross-section of a modified form, taken on a line similar to that of Fig. 4. Fig. 7 is a view of the central stem of the whistle.

Similar reference characters refer to like parts throughout the several views.

45 The whistle shown in Figs. 1, 2, 3, 4, 5, and 7 is built up of only three parts—the lower cup-shaped auxiliary bell, the main bell, and the stem. The cup 1 is provided with a screw-threaded end 2, to which the ordinary 50 whistle-valve or other connection may attach. A portion 3 is flattened to provide for engagement with a wrench. The stem has a main flat portion 4, a cap 5, a partition 6 to shorten one of the sound-chambers, the

hole 7 in the stem permitting the air in the 55 short portion above the chamber to vibrate in unison with the air in the entire chamber, thus really forming one chamber of considerable length. By this construction no length of chamber is wasted and for a given 60 length of bell two notes of maximum depth are obtained. The lower end of the stem screws into the cup 1. Between the cap 5 of the stem and the cup the bell 8 is secured. This bell is provided with two sound-openings 9, 65 as shown in Figs. 1, 3, and 4. A round head or disk 10, formed on the stem, has a series of small lugs 11, that fit against the inner wall 18 of the bell 8 to position the same. The disk 10 is of sufficiently less diameter 70 than the bell to permit the necessary amount of fluid to pass through to sound the whistle. A passage through the cup 1 connects with the passage 13 in the stem, and this in turn with the cross-passage 14, and this with the 75 space between the disk 10 and the bell.

The width of the sound-openings 9 will vary with the pressure of the steam, air, or gas used. The connecting portion 15 between the upper and lower portions of the 80 bell 8 may be of any desired width.

The stem just described is flat, and so divides the interior of the bell into two chambers. The stem may, however, be shaped with three blades 17, as in Fig. 6, or in any other 85 desirable manner.

The cup 1 is of great value when the whistle is to be used on automobiles, as it prevents flying mud and dirt from lodging in the space 90 between the bell and the disk 10.

Having now explained my improvements, what I claim as my invention, and desire to secure by Letters Patent, is—

1. In a whistle, the combination of a lower portion, a stem screwed into the same and 95 provided with an enlarged portion intermediate its ends, and a cylinder mounted on said stem, said lower portion comprising a cup-shaped bell extending longitudinally upward beyond the lower end of the cylinder to 100 inclose the same.

2. In a whistle, the combination of a stem, a cylindrical bell mounted on said stem and provided with sound-openings, and a lower portion to support the stem and bell, said 105 lower portion being provided with a cup-shaped projection which extends over the sound-openings in the bell.

3. In a whistle, the combination of a cup-shaped lower portion; a stem screwed into the same and provided with an enlarged portion and a cap, and a cylindrical bell fitting over the enlarged portion of the stem and contacting with the bottom of the cup of the cup-shaped portion, said bell having a sound-opening a distance from its lower edge.
4. In a whistle, the combination of a cylinder having sound-openings, a flat stem within the cylinder dividing its interior into two chambers, a partition on said stem adapted to limit the length of one of said chambers, the stem being provided with an opening to permit the air in the space above the partition to vibrate in unison with the air in the other chamber, and a lower portion of the whistle to support the stem.

5. In a whistle, the combination of the lower portion, a stem screwed into the same and provided with an enlarged portion intermediate its ends and a cap, and a cylindrical bell extending over the enlarged portion of the stem and between the cap and the lower portion of the whistle, said bell having a sound-opening a distance from its lower edge, and said stem having a plurality of lugs on the enlarged portion to position the lower end of the bell.

In testimony whereof I have hereunto signed my name in the presence of two subscribing witnesses.

EMMET P. GRAY.
